US00D931322S

(12) **United States Design Patent** (10) Patent No.: **US D931,322 S**
 Alfonzo et al. (45) Date of Patent: ** Sep. 21, 2021

(54) **DISPLAY SCREEN OR PORTION THEREOF WITH GRAPHICAL USER INTERFACE**(71) Applicant: **Lutron Technology Company LLC**, Coopersburg, PA (US)(72) Inventors: **Karelys Alfonzo**, Coopersburg, PA (US); **Rhodes B. Baker**, Bethlehem, PA (US); **John H. Bull**, Coplay, PA (US); **Erica L. Clymer**, Nazareth, PA (US); **Sanjeev Kumar**, Harleysville, PA (US); **Aaron Peters**, Allentown, PA (US); **Rahul Subramany**, Hellertown, PA (US); **Shannon M. Sullivan**, Coopersburg, PA (US)(73) Assignee: **Lutron Technology Company LLC**, Coopersburg, PA (US)(**) Term: **15 Years**(21) Appl. No.: **29/647,719**(22) Filed: **May 15, 2018****Related U.S. Application Data**

(63) Continuation of application No. 29/562,239, filed on Apr. 24, 2016, now Pat. No. Des. 820,862.

(51) LOC (13) Cl. **14-04**

Primary Examiner — Bao-Yen T Nguyen(74) *Attorney, Agent, or Firm* — Saidman DesignLaw Group, LLC**CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof and form no part of the claimed design.
